UNITED STATES PATENT OFFICE.

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE.

PACKER DELIVERIES FOR FOLDING MACHINES.

Application filed May 18, 1926. Serial No. 109,903.

My invention is directed to improvements in folding machines having two packer signature deliveries and particularly to manually operated means for independently changing the timing of the two sets of packer fingers with respect to their signature deliveries so that the signatures may be carried into their respective packers with a minimum amount of disturbance, said manually operated timing means being operable while the machine is running.

A practical embodiment of my invention is represented in the accompanying drawings, in which—

Fig. 1 represents the machine in side elevation.

Fig. 2 represents the machine in longitudinal vertical section.

Fig. 3 represents a detail cross section, on an enlarged scale, taken in the plane of the line III—III of Fig. 1, looking in the direction of the arrows.

Fig. 4 represents a detail cross section, on an enlarged scale, taken in the plane of the line IV—IV of Fig. 1, looking in the direction of the arrows.

Fig. 5 represents a detail cross section, on an enlarged scale, taken in the plane of the line V—V of Fig. 1, looking in the direction of the arrows.

The side frames of the machine are denoted by 1 and 2, in which side frames are mounted the upper and lower packer deliveries, comprising the usual troughs 3 and 4 and their respective sets of reciprocating packer fingers 5 and 6 uprising from their slides 7 and 8.

The means for reciprocating the sets of packer fingers is constructed, arranged and operated as follows:

A drive shaft 9 is rotatably mounted in the side frames 1 and 2. Two wide faced spiral gears 10 and 11 are mounted on and slidably interlocked with the drive shaft 9, which spiral gears mesh at all times with their respective spiral gears 12 and 13, fast on the cam shaft 14, rotatably mounted in the side frames 1 and 2. Cams 15 and 16 are also fast on the cam shaft 14, which cams reciprocate the upper and lower sets of packer fingers 5 and 6 through the rock levers 17 and 18, their rack bars 19 and 20, and the pinions 21 and 22 which mesh with the racks 23 and 24 on the bars 19 and 20

and also with the racks 25 and 26 on the packer finger slides 7 and 8 respectively.

Manually operated means are employed for independently timing the packer fingers so that the fingers will be caused to engage the signatures at the proper instant to permit the signatures to be forced into their respective packers with the minimum disturbance, which means is herein shown as being constructed, arranged and operated as follows:

A screw shaft 27 is rotatably mounted in the side frame 2 for controlling the timing of the upper set of packer fingers 5. This screw shaft 27 has a screw-threaded engagement with a yoke 28 slidably mounted on a pin 29 projecting inwardly from the side frame 1, which yoke engages the hub of the wide faced spiral gear 10, slidably interlocked with the drive shaft 9 on which it is mounted. This screw shaft 27 is provided with a suitable handle 30 located outside of the side frame 2, in position for ready manipulation to rotate the screw shaft 27 in either direction for moving the spiral gear 10 laterally with respect to its intermeshing gear 12 on the cam shaft 14, to accurately time the upper set of packer fingers 5.

Another screw shaft 31 is rotatably mounted in the side frame 2 for controlling the timing of the lower set of packer fingers 6. This screw shaft 31 has a screw-threaded engagement with a yoke 32, slidably mounted on a pin 33 projecting inwardly from the side frame 2, which yoke engages the hub of the wide faced spiral gear 11, slidably interlocked with the drive shaft 9 on which it is mounted. This screw shaft 31 is provided with a handle 34 located outside of the side frame 2 adjacent to the handle 30 of the screw shaft 27 in position for ready manipulation to rotate the screw shaft 31 in either direction for moving the spiral gear 11 laterally with respect to its intermeshing gear 13 on the cam shaft 14, to accurately time the lower set of packer fingers 6.

It is evident that various changes may be resorted to in the construction, form and arrangement of the several parts without departing from the spirit and scope of my invention; hence, I do not intend to be limited to the particular embodiment herein shown and described, but—

What I claim is:—

1. In a packer signature delivery, a plurality of sets of packer fingers, means for reciprocating them, and manually operated means for independently changing the timing of each set of packer fingers.
2. In a packer signature delivery, a plurality of sets of packer fingers, means for reciprocating them, and manually operated means for independently changing the timing of each set of packer fingers while the machine is running.
3. In a packer signature delivery, a plurality of sets of packer fingers, means for reciprocating them including a drive shaft, a cam shaft and a pair of intermeshing spiral gears thereon for each set of packer fingers, and manually operated means for sliding a spiral gear of each pair along its shaft to independently change the timing of said sets of packer fingers.
4. In a packer signature delivery, a plurality of sets of packer fingers, means for reciprocating them including a drive shaft, a cam shaft and a pair of intermeshing spiral gears thereon for each set of packer fingers, and manually operated means for sliding a spiral gear of each pair along its shaft to independently change the timing of said sets of packer fingers while the machine is running.
5. In a packer signature delivery, a plurality of sets of packer fingers, means for reciprocating them including a cam shaft, two spiral gears fast thereon, a drive shaft, two spiral gears mounted thereon and slidably interlocked therewith, said drive shaft gears intermeshing with their respective cam shaft gears, and hand operated screw shafts for separately sliding the drive shaft gears to independently change the timing of said sets of packer fingers.
6. In a packer signature delivery, a plurality of sets of packer fingers, means for reciprocating them including a cam shaft, two spiral gears fast thereon, a drive shaft, two spiral gears mounted thereon and slidably interlocked therewith, said drive shaft gears intermeshing with their respective cam shaft gears, and hand operated screw shafts for separately sliding the drive shaft gears to independently change the timing of said sets of packer fingers while the machine is running.
7. In a packer signature delivery, a main frame, a set of packer fingers, its slide, means for reciprocating the slide and thereby the fingers comprising a shaft, a cam fast thereon, a drive shaft having a spiral geared connection with the cam shaft, a rack bar operated by said cam and a pinion meshing with each packer finger slide and also with its corresponding rack bar, and hand screw shafts rotatably mounted in the frame arranged to slide their respective spiral gears on the drive shaft across the face of its intermeshing gear on the cam shaft to change the timing of the set of packer fingers.
8. In a packer signature delivery, a main frame, a plurality of sets of packer fingers, their slides, means for reciprocating the slides and thereby the fingers comprising a shaft, a plurality of cams fast thereon, a drive shaft having a plurality of spiral geared connections with the cam shaft, a rack bar operated by each cam and a pinion meshing with each packer finger slide and also with its corresponding rack bar, and hand screw shafts rotatably mounted in the frame arranged to slide their respective spiral gears on the drive shaft across the face of its intermeshing gear on the cam shaft to independently change the timing of the sets of packer fingers.
9. In a packer signature delivery, a main frame, a set of packer fingers, its slide, means for reciprocating the slide and thereby the fingers comprising a shaft, a cam fast thereon, a drive shaft having a spiral geared connection with the cam shaft, a rack bar operated by said cam and a pinion meshing with the packer finger slide and also with the rack bar, and a hand screw shaft rotatably mounted in the frame arranged to slide the spiral gear on the drive shaft across the face of its intermeshing gear on the cam shaft to change the timing of the set of packer fingers while the machine is running.
10. In a packer signature delivery, a main frame, a plurality of sets of packer fingers, their slides, means for reciprocating the slides and thereby the fingers comprising a shaft, a plurality of cams fast thereon, a drive shaft having a plurality of spiral geared connections with the cam shaft, a rack bar operated by each cam and a pinion meshing with each packer finger slide and also with its corresponding rack bar, and hand screw shafts rotatably mounted in the frame arranged to slide their respective spiral gears on the drive shaft across the face of its intermeshing gear on the cam shaft to independently change the timing of the sets of packer fingers while the machine is running.
11. In a packer signature delivery, a set of packer fingers, a cam for controlling the reciprocation of the sets of packer fingers, a drive shaft having a spiral geared connection with the cam, and manually operated means for changing the rotative position of the cam with respect to the drive shaft to change the timing of the sets of packer fingers.
12. In a packer signature delivery, a plurality of sets of packer fingers, cams for controlling the reciprocation of the sets of packer fingers, a drive shaft having a spiral geared connection with each of said cams, and manually operated means for changing the rotative position of each of the cams

with respect to the drive shaft to independently change the timing of the sets of packer fingers.

13. In a packer signature delivery, a set of packer fingers, a cam for controlling the reciprocation of the packer fingers, a drive shaft having a spiral geared connection with the cam, and manually operated means for changing the rotative position of the cam with respect to the drive shaft to change the timing of the packer fingers while the machine is running.

14. In a packer signature delivery, a plu-

rality of sets of packer fingers, cams for controlling the reciprocation of the sets of packer fingers, a drive shaft having a spiral geared connection with each of said cams, and manually operated means for changing the rotative position of each of the cams with respect to the drive shaft to independently change the timing of the sets of packer fingers while the machine is running.

In testimony that I claim the foregoing as my invention, I have signed my name this 14th day of May, A. D. 1926.

HOWARD M. BARBER.
